UNITED STATES PATENT OFFICE

2,451,923

BOTTLEHOLDER

Richard A. Cox, Gainesville, and Lewis D.
Hartsfield, Lake City, Fla.

Application February 2, 1946, Serial No. 645,035

1 Claim. (Cl. 248—311)

1

The present invention relates to new and useful improvements in holders and more particularly to a bottle holder which can be mounted conveniently on a wall or on the inside of an automobile body, to the end that a bottle or other receptacle can be sturdily supported.

An important object of the invention is to provide a bottle holder of the character stated which is constructed of heavy wire or ductile rod material arranged in such a manner as to permit manufacture at a very low cost.

Other objects and advantages of the invention will become apparent to the reader of the following specification.

In the drawings:

Figure 1 represents a fragmentary side elevational view of an automobile door showing a holder mounted in position for use.

Figure 2 is a fragmentary top plan view of the structure shown in Figure 1.

Figure 3 is a perspective view of the holder.

Figure 4 is a perspective view of a slightly modified form of holder.

Figure 5 is a perspective view of still another modified form of holder.

Referring to the drawings wherein like numerals designate like parts, it can be seen in Figure 3 that numeral 5 generally refers to one form of holder which consists in its entire construction of a single length of ductile rod or heavy wire material. This material or elongated member is formed at its intermediate portion to provide an open substantially annular form 6, the end portions of which are disposed downwardly to provide legs 7 and 8 and cross each other horizontally, as at 9 and 10, from where they extend upwardly to provide legs 11 and 12. Upper portions of these legs 11 and 12 are coiled, as at 13 and 14, around portions of the substantially annular form 6 and then extend upwardly, as at 15 and 16 to terminate in eyes 17 and 18. It is preferable that the riser 16 be substantially longer than the riser 15 to the end that the same can be conveniently bent to the right or left to take care of any obstructions that may have to be encountered on a supporting structure.

Securing elements 19 are disposed through the eyes 17 and 18 to secure the holder to the inside of an automobile door 20 or to any other structure desired.

A modification of the invention is shown in Figure 4 and generally referred to by numeral 21. This modified form consists of a ring 22, and elongated members 23 and 24. The members 23 and 24 each has one end soldered to the ring

2

22 and extends downwardly, thus providing legs 25 and 26. These legs 25 and 26 are crossed by being disposed horizontally, as at 27 and 28, from where they extend upwardly defining legs parallel to the legs 25 and 26. These legs are coiled around the ring 22, as at 29 and 30 and extend upwardly to provide a short riser 31 terminating in an eye 32 and a long riser 33 terminating in an eye 34.

10 10 A third form of the invention is shown in Figure 5 and is generally referred to by numeral 35. This form of the invention involves an ovate shaped horizontal frame 36 and a pair of elongated elements, referred to by numeral 37 and 38.

15 15 These members each has one end curled or coiled, as at 39, around one side of the frame 36 and extend downwardly to provide legs 40 and 41 which extend laterally under the frame, as at 42 and 43, from where they extend upwardly, as at 44 and 45, to coil around the opposite side of the frame 36, as at 46, and from there the members rise to provide a long leg 47 terminating in an eye 48 and a short leg or riser 49 terminating in an eye 50.

20 20 25 The form of holder shown in Figure 5 is particularly adapted for receiving bottles of the flat rectangular shape.

25 25 While the foregoing specification sets forth the invention in specific terms, it is to be understood that numerous changes in the shape, size and materials may be resorted to without departing from the spirit and scope of the invention as claimed hereinafter.

Having described the invention what is claimed 30 30 as new is:

35 35 A bottle holder comprising a wire frame having a portion thereof forming a loop with the end portions of said loop being shaped to form crossed U-shaped leg members having the terminal ends 40 40 of said wire coiled about said loop and extending above the same terminating in a supporting eye.

RICHARD A. COX.
